UNITED STATES PATENT OFFICE

EDWARD N. CAVEET, OF CHICAGO, ILLINOIS, ASSIGNOR OF ONE-THIRD TO SAMUEL PETERSEN AND ONE-THIRD TO GEORGE B. ARCHER, BOTH OF CHICAGO, ILLINOIS

SPEED-RETARDING APPARATUS FOR BOATS

Application filed October 17, 1930. Serial No. 489,318.

This invention relates to a speed retarding apparatus for boats, and an object of the invention is the provision of means adapted to be manually operated to act as a brake in retarding or reducing the speed of a vessel through the water. The appliance is particularly adapted for use in connection with small power craft, although not necessarily limited thereto, and an additional object resides in providing specially constructed braking plates which, when lowered in operative position, function to direct an increased volume of water in operative contact with the rudder whereby more positive and greater effectiveness of control is provided. More specifically, an object of the invention resides in the provision of a pair of diagonally disposed rearwardly converging vertically reciprocable plates spaced apart and operable in unison between the boat propeller and the rudder to act as a brake and means for directing an increased volume of water against the rudder when in lowered position.

25 Other objects will appear hereinafter.

The invention consists in the combinations and arrangements of parts hereinafter described and claimed.

The invention will be best understood by reference to the accompanying drawings, forming a part of this specification, and in which:

Fig. 1 is a side elevational view, partially broken away, of a boat of the small power craft type, incorporating the present invention;

Fig. 2 is a plan view of the boat shown in Fig. 1, with parts broken away to show the construction and arrangement of the incorporation of the present invention;

Fig. 3 is an enlarged vertical sectional view, taken substantially on the line 3—3 of Fig. 2;

Fig. 4 is an enlarged transverse sectional view, taken substantially on the line 4—4 of Fig. 2;

Fig. 5 is an enlarged view of one of the water-tight members for a braking plate, taken substantially on the line 5—5 of Fig. 4;

Fig. 6 is a detail view, taken substantially on the line 6—6 of Fig. 5; and

Fig. 7 is a horizontal sectional view showing the connection of the braking plates, taken substantially on the line 7—7 of Fig. 4. 55

As illustrated in the drawings, the invention is shown applied to a boat having a hull 10, rudder 11, propeller 12, and steering wheel 13. The preferred embodiment of the present invention comprises a right braking plate 14 and a left braking plate 15. In order to enable these plates to be elevated and lowered and extend through the hull at a point normally below the water line, each plate is preferably rectangular in cross-sectional outline, and, as shown in Fig. 7, the plates are disposed in diagonal position to converge rearwardly. Furthermore, the plates 14 and 15 are preferably spaced a substantial distance, as shown in Fig. 4, so as 70 to be disposed on either side of the longitudinal center of the boat and correspondingly on either side of a longitudinal line extending through the propeller shaft and the rudder. In addition, the two plates are positioned transversely between the propeller and the rudder, and by this construction and arrangement when in lowered position, not only is the speed of the boat retarded by reason of the resistance offered by the forward 80 surfaces of the plates, but an increased volume of water is directed against the rudder, offering more effective steering control by the pilot. The two plates 14 and 15 are united adjacent their upper extremities by a transverse yoke 16, which in turn is secured to the lower end of a vertically extending rack 17. Rack 17 is guided for vertically reciprocating motion by direct contact with the inner surfaces of a guide housing 18 which may extend upwardly from the deck in a small boat, as shown.

Rack 17 is provided with a plurality of rack teeth 19 arranged to mesh with the teeth on pinion 20 which is secured to transverse shaft 21 journaled in bearings 22. In order to effectuate water-tight engagement, each plate 14 and 15 reciprocates through a lower plate 24 and an upper plate 25, as shown in Fig. 6. Inasmuch as these water-tight plates are iden- 103

tical for both the braking plates, a description of one set will suffice. The lower plate 24 is provided with a central slot 26 slightly larger than the cross-sectional area of the enclosed braking plate, and the upper plate 25 is provided with a similar central slot 27. The slot 26 in the lower plate 24 is preferably recessed to receive a gasket or packing 28, and adjusting bolts 29 extend through the upper plate 25 and are threaded into the lower plate 24 for compressing the gasket 28 when necessary for water-tight engagement, the lower plate 24 being secured to the hull by screws 30. As shown, the mounting is preferably directly above the tunnel stern where this method of boat construction is employed for shallow water.

A drum 31 is secured to shaft 21 and carries several turns of a cable 32 which extends forwardly and is wound on a smaller drum 33 secured to wheel 34 journaled in bearing 35. As shown, wheel 34 is provided with an operating handle 36 and is conveniently located adjacent the steering wheel 13 so as to be accessible to the pilot.

The operation will be mainly apparent from the foregoing description. When desired, the plates may be lowered by the mere expedient of rotating wheel 34 in a counter-clockwise direction by means of handle 36, using only the left hand and leaving the right hand for operation of the steering wheel 13. The braking plates may be lowered to any desired position, but in lowermost position, available when in extremely shallow water, it will be noted that the lower extremities of the braking plates extend below the hull and thus intercept the water current passing beneath the boat, which increases the effectiveness of the braking function.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. The combination with a boat, of a right braking plate, a left braking plate, a watertight connection between each plate and the hull of the boat, said plates disposed angularly with relation to each other and arranged to converge rearwardly, and manually operable means for elevating and lowering said plates, said plates in lowered position disposed upon either side of the longitudinal center of the boat, and said plates in lowered position disposed transversely between the boat propeller and the boat rudder.

2. The combination with a boat, of a right braking plate, a left braking plate, a watertight connection between the boat hull and each of said plates, a rack secured to said plates, a pinion engaging said rack, and manually operable means for rotating said pinion to elevate or lower said plates in unison. 70

3. The combination with a boat, of a right braking plate, a left braking plate, a watertight connection between the boat hull and each of said plates, a rack secured to said plates, a pinion engaging said rack, and manually operable means for rotating said pinion to elevate or lower said plates in unison, said plates in lowered position disposed upon either side of the longitudinal center of the boat. 75

4. The combination with a boat, of a right braking plate, a left braking plate, a watertight connection between the boat hull and each of said plates, a rack secured to said plates, a pinion engaging said rack, and manually operable means for rotating said pinion to elevate or lower said plates in unison, said plates in lowered position disposed transversely between the boat propeller and the boat rudder. 80

5. The combination with a boat, of a right braking plate, a left braking plate, a watertight connection between the boat hull and each of said plates, a rack secured to said plates, a pinion engaging said rack, and manually operable means for rotating said pinion to elevate or lower said plates in unison, said plates in lowered position disposed upon either side of the longitudinal center of the boat, and said plates arranged to converge in a rearward direction. 95

6. The combination with a boat, of a right braking plate, a left braking plate, a watertight connection between the boat hull and each of said plates, a rack secured to said plates, a pinion engaging said rack, and manually operable means for rotating said pinion to elevate or lower said plates in unison, said plates in lowered position disposed transversely between the boat propeller and the boat rudder, and said plates arranged to converge in a rearward direction. 100

7. The combination with a boat, of a right braking plate, a left braking plate, a watertight connection between the boat hull and each of said plates, a rack secured to said plates, a pinion engaging said rack, and manually operable means for rotating said pinion to elevate or lower said plates in unison, said plates in lowered position disposed upon either side of the longitudinal center of the boat, said plates in lowered position disposed transversely between the boat propeller and the boat rudder, and said plates arranged to converge in a rearward direction. 115

In testimony whereof I have signed my name to this specification.

EDWARD N. CAVERT.
